REMOTE CONTROL SYSTEM

Joseph George Karlet, Roanoke, and Alvan Grayson Walker, Salem, Va., assignors to The Union Switch and Signal Company, Swissvale, Pa., a corporation of Pennsylvania

Application October 30, 1947, Serial No. 783,032

4 Claims. (Cl. 177—353)

1

Our invention relates to remote control systems for the control of movable devices from a central office, and for the indication of such devices at said office by means of impulse codes transmitted over a line circuit extending from the office through a plurality of field stations at which the controlled devices are located.

Our invention is particularly adapted for use in centralized traffic control systems for railroads, and is an improvement upon that disclosed in Letters Patent of the United States No. 2,229,249, granted January 21, 1941, to L. V. Lewis for Remote control systems.

The principal object of our invention is to increase the number of devices which can be indicated or controlled by a remote control system of the type described in this patent, in which the various control and indication codes consist of groups of code elements of two kinds arranged in different combinations, and in which each code is capable of controlling or indicating a plurality of independent devices.

In the remote control system of this patent, coding units are provided at the control office and at each of a plurality of field stations, each comprising an assembly of relays for generating, transmitting, receiving and selecting code signals. The coding units are connected by a single line circuit which is normally energized by a source of current at the office, over which the codes are transmitted by recurrently interrupting or varying the line current to produce a series of code elements each of which is relatively short or long.

Typically each code comprises a series of sixteen steps arranged in two groups of eight elements each. The character of the first element designates the direction of transmission, and the remaining seven steps of the first group are arranged in a distinctive combination of three long and four short steps constituting a distinctive code call by which a selector relay is selectively operated at a particular station along with a similar relay at the office which selects an individual panel including the control levers and indication relays for the selected station. By reason of this selection, the second group of impulses is received at the selected station or control panel only. In an indication code of sixteen steps, for example, the second group includes seven elements which are governed individually in accordance with the condition of seven different devices at the transmitting station, together with a "delivery" step for operating indication stick relays, selected in accordance with the code call, by which the character of these seven elements is registered and

2

stored until changed by a succeeding code having the same code call, this delivery step also serving to return the apparatus to its normal at rest condition.

Our invention relates more particularly to the more efficient utilization of this second group of code impulses by which a plurality of independent devices may be controlled or indicated by the same code, and provides means whereby these impulses may be used either singly or in combination, thereby enabling the remote control system to control or indicate larger numbers of devices without any material change in its basic structure or mode of operation.

Our invention is applicable to both the control and indication portions of the remote control system, but inasmuch as the operation of these two portions is generally similar it is considered that a description of but one will suffice for an understanding of our invention, and accordingly our invention is described herein only in connection with the indication portion of the system, that is to say, the portion of the system which relates to the transmission of indications from a typical field station and their registration at the control office. Furthermore, since the system shown in the patent is in wide commercial use and its detailed mode of operation is widely known, it is deemed sufficient to illustrate in the accompanying drawings only those portions of the system which have been modified in accordance with our invention and which differ from the corresponding portions as shown in the patent.

One form of apparatus embodying our invention will now be described and its novel features will then be pointed out in claims.

In the accompanying drawings, Fig. 1 is a representation of the track plan of a typical layout of interlocked track switches and railway signals which a single station unit of the remote control system of the patent referred to is capable of controlling and indicating when modified in accordance with our invention, this group of apparatus requiring the transmission of twenty-one different indications, or three times as many as the station unit is capable of transmitting when arranged as shown in the patent. Fig. 2 shows the circuits for twenty-one indication relays for registering and storing these indications, all of which are governed by a single selector relay 234S in accordance with the condition of the register relays 09-016 of the patent, in place of the indication relays 9K-15K shown in Fig. 5 of the patent. The circuits for these relays as shown herein in Fig. 2 replace the corresponding portion

of the office apparatus comprising Figs. 1 to 5 of the patent. Fig. 3 of the accompanying drawings shows typical circuits for a set of indication lamps associated with the switch and signal levers SW and SG of the operator's control panel or located in a track diagram comprising a miniature replica of Fig. 1, as controlled by the indication relays of Fig. 2. Figs. 4A and 4B, taken together, illustrate the apparatus at a typical field station as modified to govern the transmission of the code elements by the various wayside devices for controlling the indication relays of Fig. 2, these circuits being arranged to replace the transmission control circuits shown in the lower portions of Figs. 7 and 8 of the patent, in the system illustrated therein by Figs. 6 to 9, inclusive.

Similar reference characters refer to similar parts in each of the views, and the reference characters correspond generally to those of the patent.

Referring to Fig. 1 of the accompanying drawings, it will be seen that the track layout chosen to illustrate our invention includes seven track sections designated 1T to 7T, inclusive. Each of these sections has a correspondingly numbered track relay TR shown herein in Fig. 4A or 4B which it is to be understood is included in a closed track circuit like relay 4TR in Fig. 9 of the patent. Each relay TR governs the transmission of a code element for controlling a correspondingly numbered track indication relay TK in Fig. 2 of the attached drawings by which the condition of occupancy of the track section is indicated and which replaces the relay 9K or 11K shown in Fig. 5 of the patent.

The four crossover tracks in Fig. 1 are equipped with the usual power switch machines identified by the numbers 1, 3, 5, and 7, respectively, with a suffix A or B. It will be understood that these are conventionally arranged and that the two switches of each crossover jointly control the correspondingly numbered normal and reverse repeating relays NWP and RWP of Fig. 4A or 4B in the manner illustrated by the repeating relay RWP or by the correspondence relays NKR and RKR of Fig. 9 of the patent. Each switch repeating relay governs the transmission of a code element for controlling the corresponding switch indication relay NWK or RWK in the attached Fig. 1, which relays replace the relays 13K and 15K shown in Fig. 5 of the patent.

Train movements into the track layout of Fig. 1 are governed by three pairs of opposing signals identified as shown by the numbers 2, 4, and 6 with the suffix R or L. It is to be understood that each signal or group of signals controls a correspondingly numbered signal indication relay LGP or RGP as shown in Fig. 9 of the patent. These relays, shown in the accompanying Fig. 4A, govern the transmission of code elements for controlling the signal relays LHK and RHK of Fig. 1; whereas, in the patent three code steps are employed for indicating signal conditions herein one of these is eliminated by interconnecting the signal lamp circuits as shown in the accompanying Fig. 3.

It is to be understood that the code register relays 09 to 016, inclusive, in Fig. 2 are governed like the similarly designated relays shown in Fig. 1 of the patent, and that the selector relay 234S corresponds to any one of the relays 234S—678S shown in Fig. 2, 3 or 4 of the patent, but that the single delivery relay D which each selector relay controls in the system of the patent is replaced in accordance with our invention by a

series of delivery relays 1D to 6D, inclusive. Where in the patent, a group of seven indication relays selected by an S relay are operated in accordance with the condition of the register relays 09 to 015, following the operation of relays 016 and D at the end of each code herein, a particular delivery relay of the series 1D to 6D is selected for operation by relay 016 jointly by relay S and by the first one of the register relays 09 to 015 to be operated, and thus the selected delivery relay operates a sub-group of from one to six indication relays in accordance with the condition of those register relays, the operation of which follows that of the one by which such delivery relay is operated. Thus the total number of devices the condition of which may be indicated simultaneously by any code varies from one to six, but the total number of different devices the condition of which may be indicated by a single coding unit, by the transmission of successive codes, is twenty-one instead of seven as heretofore.

Referring now to Figs. 4A and 4B, which show the corresponding field station transmitting apparatus, it is to be understood that relay M is the master relay of Fig. 6 of the patent which governs the transmission of indication codes as described therein, that relay S, Fig. 4B, is the station selector relay shown in Fig. 7 of the patent, and that relays 9 to 16 are register relays which operate in unison with the office register relays 09 to 016 on correspondingly numbered long steps of each transmitted code. Relays 9 to 12 are controlled as shown in Fig. 6 of the patent, and it is to be understood that relay 13 as well as the additional relays 14 and 15 not shown in the patent are controlled similarly, but on steps 13 to 15 of each code. Each of the six sub-groups of from one to six indicating relays shown in Figs. 4A or 4B is provided with an individual starting relay 1ST to 6ST, respectively, which replace the single starting relay ST of the station unit shown in Fig. 7 of the patent, and each sub-group has a control relay, 1MSP to 6MSP, which is selected for operation by the associated starting relay. The relays MSP are operated only one at a time by relays M and S and each serves to govern the character of a different one of the steps 9—15 of a transmitted code in such a manner as to select the corresponding one of the series of delivery relays 1D—6D associated with the corresponding office selected relay such as relay 234S. Each relay MSP also governs the transmission of the code elements which reflect the condition of the indicating relays of its group like the relay MSP shown in Fig. 7 of the patent.

Each sub-group at the station also has a series of valve relays V and a valve control relay VC for operating the relays V in accordance with the condition of the relays 10 to 15 in response to the operation of relay 16 at the end of the code. These relays V and VC function to open the starting circuit when a code initiated in response to a change in condition of one or more of the indicating relays is fully transmitted, like the similarly designated relays in Fig. 7 of the patent.

Considering now the mode of operation of the apparatus of our invention under different assumed conditions, it will be assumed first that a train approaching signal 4R enters section 6T in Fig. 1 releasing the track relay 6TR in Fig. 4B. Relay 6TR completes a circuit from one terminal B of the local source of current over its back contact *d*, back contacts *g* of relay 5MSP

and *c* of relay 5V through the winding of the starting relay 5ST to the other terminal *C* of the source, and relay 5ST picks up, completing a stick circuit at its contact *a* extending to terminal *B* at back contact *j* of relay 5VC.

The closing of contact *c* of relay 5ST completes a circuit over wire 38 for relay M, which picks up to initiate the transmission of an indication code, on the fourth step of which the station selector relay S becomes energized as described in the patent by reason of the connection established between wires 41 and 49 over contact *b* of relay 5ST, whereupon a circuit is closed from terminal *B* at front contact *c* of relay M, Fig. 4B, over front contact *c* of relay S, and the back contact *j* of each of the relays 6MSP to 1MSP, and thence over back contacts *d* of relays 1ST to 4ST, front contact *d* of relay 5ST through relay 5MSP to terminal *C*.

Relay 5MSP therefore picks up and establishes a stick circuit at its front contact *j*. The opening of this back contact *j*, as will readily be seen from the drawing, opens the pick up circuits for all of the relays MSP and it follows that only one relay MSP will assume its energized position even though additional starting relays ST become energized, and the indication codes initiated in different sub-groups are transmitted successively without interference.

Relay 5MSP directly governs the operation of relays 13 to 15, by closing its front contacts *e*, *f*, and *g*, and by preventing the operation of relays 1MSP to 4MSP as above described, causes relays 9 to 12 to remain released. Relay 13 becomes energized in the manner explained in the patent because terminal *B* at contact *e* of relay 5MSP is connected to wire 43; relay 14 remains released because wire 44 is not energized, and relay 15 becomes energized because wire 55 is connected to terminal *B* over back contact *d* of relay 6TR and front contact *g* of relay 5MSP. Relay 16, Fig. 4A, operates in the usual manner on the final step of the code and by connecting terminal *B* to wire 30 at its contact *c* energizes relay 5VC over front contact *h* of relay 5MSP.

Terminal *B* at contact *c* of relay 15 is now connected to wire 17, so that relay 55V picks up in response to the closing of front contact *g* of relay 5VC, and is held energized over its stick circuit after relay 5VC is released at the end of the code. Relay 5VC also releases the starting relay 5ST, and relay 55V by closing its front contact *c* prepares a new pick up circuit for relay 5ST to enable a succeeding code to be initiated following the reenergization of relay 6TR. The release of all of the relays operated during the transmission of the code referred to, except relay 55V, occurs at the end of the code as described in the patent.

Considering now the mode of reception at the control office of the code just described, it will be understood that a selector relay 234S, Fig. 2, which identifies the transmitting station, is operated along with the selector relay S at that station, and that the positions assumed by the office register relays 09-015 is the same as that of the relays 9-15 at the transmitting station. In this particular code, therefore, relays 09-012 and 014 remain released, but relays 013 and 015 become energized upon the reception of the corresponding code elements so that, when relay 016 becomes energized on the final delivery step of the code, wire 118 is connected to terminal *B* at its contact *c* as described in the patent, and a circuit is completed from wire 118 over back contacts *d* of relays 09-012, front contact *d* of relay 013, 75

contact *k* of relay 234S through relay 5D to terminal *C*. Relay 5D picks up and since relay 014 is released, wire 114 is not energized, and relay 5TK is released by relay 5D, if energized. Relay 6TK is picked up over wire 115 by the closing of front contact *a* of relay 5D and is held energized by its stick circuit after relay 5D is released at the end of the code, thereby indicating the occupancy of section 6T by the lighting of a suitable lamp TKE, Fig. 3.

It will next be assumed that a code is initiated by a change in the condition of one of the indicating relays which controls relay 1ST, Fig. 4A. In this case relay 1MSP becomes energized and the closing of its contact *a* connects terminal *B* to wire 39 to prolong the ninth step of the transmitted code and thereby energize relays 9 and 09. On the sixteenth step relay 1D, Fig. 2, is energized over wire 118, front contact *d* of relay 09 and front contact *g* of relay 234S and relay 1D governs the six indication relays of its group in accordance with the positions of the relays 010 to 015.

It will be seen that each indication relay in Fig. 2 is governed by a combination of code impulses. Relays 1TK and 2TK, for example, are controlled in accordance with the character of the tenth and eleventh steps of only those codes which have a long ninth step, while relay 3TK is controlled in accordance with the character of the eleventh step of only those codes in which the ninth step is short and the tenth step is long.

From the typical examples given in the foregoing description, it is believed that the operation of the apparatus will be clearly understood, and that it will be readily apparent that each coding unit of the remote control system may be readily modified in accordance with our invention so as to be rendered capable of controlling or indicating the condition of a materially larger number of devices by the provision of a relatively small number of additional relays, resulting in a marked economy in the amount of apparatus required, particularly in the case of larger installations.

Although we have herein shown and described only one form of apparatus embodying our invention, it is understood that various changes and modifications may be made therein within the scope of the appended claims without departing from the spirit and scope of our invention.

Having thus described our invention, what we claim is:

1. In a remote control system for controlling a plurality of indication relays each in accordance with the condition of a different movable device, having transmitting means for generating different codes, each comprising a series of code elements of a first or second character, said elements being transmitted one at a time so that each element is identified by the number of elements which precedes it, said system having receiving means including a series of register relays each identified with a different code element of said series with means for operating each register relay upon the reception of the code element with which such relay is identified provided it is of said second character, said system also having a series of starting relays for initiating the operation of said transmitting means, including one for each of a plurality of groups of said movable devices, each starting relay being operated in response to change in condition of any movable device in its group, said starting relays

being arranged to govern the transmission of codes one at a time when a plurality of such relays are operated, the combination with the foregoing of means controlled by each operated starting relay which is governing the transmission of a series of code elements for imparting said second character to a different one of the code elements of said series whereby the group of movable devices with which such starting relay is associated is identified by the number of elements of said first character which precede the element of said second character, means controlled by such starting relay for enabling the movable devices of its group to govern the character of each of the succeeding elements of said series even though such elements are adapted to identify other groups of devices in codes governed by other starting relays, and means governed by the first of said series of register relays to be operated by a code element of said second character for selecting a particular group of said indication relays for operation in accordance with the condition of the register relays identified with the succeeding elements of said series.

2. In a remote control system having transmitting means for generating a code comprising two groups of code elements and also having a receiver responsive to said code containing a selector relay which is energized in response to a distinctive code pattern of the elements in the first group in a received code; a plurality of delivery relays, a group of stick relays for each delivery relay, means controlled by said selector relay when energized for selecting each of said delivery relays for operation, means for energizing a particular one of said delivery relays in accordance with the code pattern of one or more of the code elements of the second group in a received code, and means controlled by the energized delivery relay for selecting the stick relays of the corresponding group for operation in accordance with the character of the remaining code elements in said second group of elements, even though one or more of such elements are adapted to govern other delivery relays in response to codes having different code patterns.

3. In a remote control system having transmitting means for generating a code comprising two groups of code elements and also having a

receiver responsive to said code in which a selector relay is energized in response to a distinctive code pattern of the elements in the first group in a received code; a plurality of delivery relays controlled by said selector relay, a plurality of indication relays controlled by each delivery relay, means for selecting each delivery relay for operation in accordance with the character of a different element in the second group of elements in a received code, means effective at the end of such code for energizing the delivery relay corresponding to a particular element in said second group only if no delivery relay corresponding to a preceding element has been selected, and means controlled by the energized delivery relay for operating the indication relays of its group in accordance with the character of the succeeding code elements in said second group.

4. In a remote control system having transmitting means for generating a code comprising a group of elements, each of which is of a first or a second character, and also having a receiver responsive to said code including a plurality of delivery relays, one for each of a plurality of the code elements in said group, means for selecting each delivery relay for operation at the end of the code when the corresponding code element is of said second character and each preceding code element in said group is of said first character, a plurality of groups of indication relays including one for each delivery relay, and means for operating the indication relays of the group identified by the operated delivery relay each in accordance with the character of a different one of the code elements which follow the one by which such delivery relay is selected.

JOSEPH GEORGE KARLET.
